UNITED STATES PATENT OFFICE.

SHERWOOD VERMILYE, OF LOUISVILLE, KENTUCKY, ASSIGNOR TO LOUISVILLE DRYING MACHINERY CO. INC., OF LOUISVILLE, KENTUCKY, A CORPORATION OF KENTUCKY.

ROTARY COOLER.

Application filed April 27, 1927. Serial No. 186,914.

My invention relates to rotary coolers which are particularly suitable for material entering the dryer at a high temperature, which affects the expansion and contraction 5 of the cooler. This cooler is an improvement over Patent No. 1,617,815, from which it differs in the provision of means for permitting the tubes that carry the cooling medium to expand and contract relative to 10 the body of the cooler.

In the appended drawing, Figure 1 is a longitudinal broken section on line 1—1, Figure 2, and

Figure 2 is a transverse section on line 15 2—2, Figure 1.

In the drawing, 3 represents the drum of the cooler which is provided at the ends with heads 4 and 5, respectively. To the head 4 are anchored the series of tubes 6 through 20 which the cooling medium is to be circulated. The other ends of the tubes project through the head 5 into a stationary housing 7 located in proximity to the head 5. The housing 7 is provided with a suitable aperture 8 to accommodate the loading hopper 9 through 25 which the material to be cooled may be discharged into the cooler through the head 5.

Each of the tubes entering the housing 7 is provided with a valve 10 and a nozzle 11. 30 Only two are shown in Figure 2, the rest are omitted. Each nozzle is inclined from the vertical plane and also away from the direction of rotation so as to reduce the splashing of the cooling medium discharged 35 by each of the tubes.

The cooling medium is supplied to the tubes through the head 4 by a manifold 12. The manifold is connected to an axial revolving pipe 13 which carries a stuffing box 40 14 connected with a stationary supply pipe 15. The material from the cooler is discharged through the central part of the head 4 to a stationary casing 16 through which the pipe 13 projects. It therefore will be noted 45 that the flow of the material and that of the cooling medium are in opposite directions.

To further reduce the splashing of the cooling medium in the housing 7, a semi-circular concave trough 17 is formed in the 50 housing below the aperture 8 for the loading hopper 9. This trough 17 receives the cooling medium which is discharged by the nozzles above or runs on the walls forming the aperture 8 and also whatever is reflected 55 by the outer wall 18 of the housing 7 into the

said hopper or the wall above it. In addition, the housing 7 has an upper semi-circular convex trough 19, which is formed about the outer row of tubes 6 in the upper part of the housing 7. This trough 19 joins 60 the outer wall 18 of the housing 7 by an inclined peripheral wall 20 which directs any cooling medium that tends to rise to the periphery of the upper half of the housing 7 into the trough 19, which therefore will 65 cause the cooling medium entering thereto to fall into the lower part of the housing 7 without striking any of the discharge nozzles and valves of the tubes 6 directly below it. At the lower part of the stationary housing 70 7, there is a main discharge 20 and a secondary discharge 21 leading from the lower part of the semi-circular trough 17 to the discharge 20, as best seen in Figure 1.

By providing the stationary housing with 75 the upper and lower troughs, the splashing of the cooling medium within the housing is reduced to a minimum and therefore the in-leakage of the cooling medium along the tubes 6 through the head 5 into the cooler 80 is also prevented. If desired, suitable packing glands may be provided in the head 5 for the tubes 6, which will prevent any inleakage, but will permit a free expansion and contraction of the tubes 6 in the cooler. 85

I claim—

1. In a cooler, a plurality of tubes for carrying a cooling medium, said tubes being anchored at one end and free to move longitudinally at the other, a housing receiving 90 the free end of the tubes, means for supplying the anchored ends of the tubes with the cooling medium and means at the free ends of the tubes for controlling and directing the discharge of the cooling medium into the 95 housing.

2. In a cooler, a plurality of tubes, one end of which is anchored and the other is free to move longitudinally under the expansion and contraction, means for supplying cooling medium to the anchored ends of the tubes, means for controlling and directing the discharge of the cooling medium from the tubes at the free end thereof, a housing receiving the free ends of the tubes into 100 which the cooling medium is discharged and means carried by said housing to reduce the splashing therein of the discharged cooling medium.

3. In a cooler, a plurality of tubes, one end 110

- of each tube of which is anchored and the other is free to move longitudinally, means for supplying cooling medium to the anchored ends of the tubes, nozzles at the free ends of the tubes for directing the flow of the cooling medium in a predetermined direction, a housing receiving said nozzles and means within said housing adapted to prevent the upper nozzles from discharging onto the lower nozzles.
4. In a cooler, a plurality of tubes disposed circumferentially for carrying a cooling medium, said tubes being anchored at one end and free to move longitudinally at the other, a housing receiving the free ends of the tubes, means for supplying the anchored ends of the tubes with cooling medium, means at the free ends of the tubes for controlling the discharge of the cooling medium and a concave trough within the circumference of the tubes for receiving some of the cooling medium within the housing.
5. In a cooler, a plurality of tubes disposed circumferentially, said tubes being anchored at one end and free to move longitudinally at the other, a housing receiving the free ends of the tubes, means for supplying the anchored ends of the tubes with cooling medium, means at the free ends of the tubes for controlling the discharge of the cooling medium, a trough within the circumference of the tubes and a trough out of the circumference of the tubes for receiving some of the cooling medium discharged into the housing to reduce splashing therein.
6. In a cooler, a plurality of tubes disposed circumferentially, and adapted to rotate, said tubes being anchored at one end and free to move longitudinally at the other, a stationary housing receiving the free ends of the tubes, means for supplying the anchored ends of the tubes with cooling medium, means at the free ends of the tubes for controlling the discharge of the cooling medium into the stationary housing, a concave trough carried by the housing within the circumference of the tubes for receiving some of the cooling medium discharged into the housing, a convex trough carried by the housing in the upper part thereof outside of the circumference of the tubes also for receiving some of the cooling medium discharged into the housing and means for removing the cooling medium from the housing.

SHERWOOD VERMILYE.
